UNITED STATES PATENT OFFICE

THEODORE JOHNSON, OF ERIE, PENNSYLVANIA, ASSIGNOR TO JOHNSON METAL PRODUCTS CO., OF ERIE, PENNSYLVANIA

LOCKING MEANS FOR CASEMENT WINDOWS

Application filed December 4, 1928. Serial No. 323,701.

This invention relates to locking means for casement windows and it is an object of the invention to provide a device of this kind which can be employed with equal facility at 5 the right or left side of the window.

It is also an object of the invention to provide a device of this kind comprising a rotary locking member carried by the casement frame or other stationary part for engagement 10 with the window when in closed position to hold the same against opening movement.

The invention consists in the details of construction and in the combination and arrangement of the several parts of my improved locking means for casement windows whereby certain important advantages are attained and the device rendered simpler, less expensive and otherwise more convenient and 15 advantageous for use, as will be hereinafter more fully set forth.

The novel features of my invention will hereinafter be definitely claimed.

In order that my invention may be the better understood, I will now proceed to describe 25 the same with reference to the accompanying drawings, wherein:

Figure 1 is a fragmentary elevational view illustrating a locking means constructed in 30 accordance with an embodiment of the invention;

Figure 2 is a sectional view taken substantially on the line 2—2 of Figure 1;

Figure 3 is a fragmentary view in elevation 35 of the window with the plate comprised in my improved locking means applied thereto;

Figure 4 is a view partly in vertical section and partly in elevation of the locking means as illustrated in Figure 1 with the locking 40 member in locking position, an associated operating member being diagrammatically indicated by broken lines;

Figure 5 is a view in end elevation of the 45 rotary locking member as herein employed;

Figure 6 is an elevational view of the cup 50 member herein employed unapplied;

Figure 7 is an elevational view of the retaining washer for coaction with the rotary locking member;

Figure 8 is a fragmentary elevational view

illustrating a locking means constructed in accordance with a further embodiment of my invention, the operating member being omitted;

Figure 9 is a sectional view taken substantially on the line 9—9 of Figure 8;

Figure 10 is a sectional view taken substantially on the line 10—10 of Figure 9;

Figure 11 is an elevational view of the 60 mounting washer removed;

Figure 12 is an elevational view of the retaining member for coaction with the mounting washer and unapplied.

As disclosed in the accompanying drawings, F denotes a casement frame of desired 65 design and dimensions and with which is associated a swinging window sash W. The vertical member 1 has secured thereto by the screws 2 or the like, the end portion of a plate 3 extending inwardly beyond the out-swinging member 1^a of the sash W when the sash W is in closed position. The outer portion of the plate 3 is formed to provide an inwardly facing cylindrical housing 4 overlapping the closing face of the swinging sash or member W. The housing 4 is provided at the axial center of its outer wall with a relatively large opening 5. Arranged within the housing 4 is a cylindrical head 6 one end portion of which extends through the opening 5 while the opposite or inner end of the head 6 has disposed radially thereacross and integrally formed therewith a locking bar 7, the ends 8 of which are inwardly beveled.

A portion of the head 6 within the housing 4 is provided with an outstanding circular flange 9 with which engages a cup member 10 snugly received within the housing 4 through the inner open face thereof. This cup member 10 serves to maintain the head 6 in applied position with respect to the housing 4, yet permits the same to have requisite rotation. The outer face of the member 10 is provided with the radial slot 11 having its intermediate portion transversely enlarged beyond opposite sides thereof as at 12 to facilitate the desired assembly of the member 10 and the head 6 with respect to the housing 4.

Interposed between the flange 9 and the adjacent outer wall 14 of the housing 4 is an 100

undulated spring washer 15 which serves to provide effective means to retain the head 6 in its different positions.

The outer end of the head 6 is continued by an ear or lug 16 to which is adapted to be operatively engaged a desired operating member diagrammatically indicated at 17 in Figure 4.

Secured to the member 1^a of the sash W by the screws 18 or the like is an end portion of a plate 19 also disposed inwardly of the sash W and which, when the sash W is in closed position is in overlying relation with respect to the plate 3 and more particularly the housing 4. The inner or free end portion of the plate 19 is provided with an oval shaped opening 20 through which the bar 7 is adapted to be disposed when said bar 7 has its longitudinal axis disposed in the same general direction as the major axis of the opening 20.

Upon turning movement of the bar 7 and preferably a quarter turn it will be readily noted that the window W will be effectively locked in fully disposed position. As illustrated in Figure 4, it is to be noted that the marginal edge defining the opening 20 is closed on a bevel complimentary to a bevel on the edge of the bar 7 to facilitate the requisite locking coaction between the bar 7 and plate 19.

It is to be noted that a locking means as herein disclosed is of a character to permit the same to be used either right hand or left hand and which is of material advantage both with viewpoints of production and application.

In the embodiment of my invention as illustrated in Figures 8 to 12 inclusive I employ a housing 4' comprising a pair of spaced plates 21 and 22 having their outer margins connected by an interposed plate 23 and the opposite ends thereof closed by the interposed plates 24. The outer corner portions of the housing 4' are preferably cut away, as at 25, so that the interior of said housing may be maintained free of such dirt or the like which may have a tendency to interfere with the effective operation of the locking plate 7'. In other words, the cut out portions 25 provide convenient cleanout openings.

The inner face of the housing 4' is open and the side plates 24 are continued by the extended portions 24' which are disposed a desired distance beyond the open inner face of the housing 4' and the flanges 24 and 24' are defined by the outstanding flanges 26 which are substantially coplanar with the plate 22. The ends of the flanges 26 beyond the open face of the housing 4' are welded or otherwise securely attached to an adjacent vertical member 1' of a casement frame F'.

The central portions of the plates 21 and 22 are provided with the relatively large aligning openings 27 and snugly fitting within the opening 27 of the outer plate 22 is an

inwardly disposed boss 28 carried by the central portion of a supporting washer 29. This boss 28 and washer 29 have disposed therethrough an opening 30 angular in cross section and through which is snugly directed a shank 31. This shank 31 is also snugly directed through an opening 32 formed in an end portion of the locking plate 7' with the head 33 of the shank 31 having contact with the inner or rear face of the locking plate 7'. Threaded upon the shank 31 for coaction with the mounting washer 29 is a holding nut 34 and interposed between the applied nut 34 and washer 29 is an undulated spring washer 35 which serves to provide effective means to hold the nut 34 against retrograde rotation upon the shank 31.

The shank 31 may be readily applied in desired working position through the opening 27 in the inner or rear plate 21 after the plate 7' has been properly inserted within the housing 4' through the inner open face thereof and the mounting washer 29 has also been applied. After the nut 34 has been properly engaged upon the shank 31 the locking plate 7' will be effectively supported within the housing 4' for rotation with the shank 31.

The shank 31 is of a length when applied to extend a material distance beyond the outer face of the housing 4' and the free end portion of the shank 31 is cylindrical in form, as at 37, with its periphery preferably smooth and unobstructed. This portion 37 of the shank 31 is snugly engaged within a socket or recess 38 provided in the inner face of a head 39 and keyed thereto by a pin 40 or the like. The head 39 has the marginal portion of its inner face defined by a skirt 41 disposed in a direction toward the washer 29 and which serves to substantially house or enclose the applied nut 34.

Pivottally connected, as at 42, with the outer portion of the head 39 is an operating handle 43 which provides convenient means to impart the requisite rocking movement to the shank 31 and the locking plate 7'.

The frame F' has associated therewith an out-swinging sash S and the out-swinging vertical member 1^b thereof at a desired point thereon has bolted as at 44, or otherwise securely attached thereto an outstanding keeper 45 which, when the sash S is in applied position with respect to the frame F', projects between the extended portions 24' of the end plates 24 and in proper position to receive an end portion of the plate 7' upon requisite swinging movement of the shank 31 whereby the sash S is effectively locked in fully closed position.

From the foregoing description it is thought to be obvious that a locking means for casement windows constructed in accordance with my invention is particularly well adapted for use by reason of the convenience

and facility with which it may be assembled and operated, and it will also be obvious that my invention is susceptible of some change and modification without departing from the 5 principles and spirit thereof and for this reason I do not wish to be understood as limiting myself to the precise arrangement and formation of the several parts herein shown in carrying out my invention in practice except as hereinafter claimed.

I claim:—

1. In combination with a support and a closure member coacting therewith, a housing carried by the support and overlapping the closing face of the member when in closed position with respect to the support, said housing having a face wall outwardly offset with respect to the adjacent face of the support, a shank rotatably supported by said 20 offset face wall of the housing, means for rotating said shank, and a locking means carried by the shank engageable upon rotation of the shank with the member to hold the same in closed position with respect to the support, said shank being inserted through the housing from the rear, the operating means for the shank being engaged with the opposite end portion of the shank.

2. In combination with a support and a 30 swinging member coacting therewith, a housing carried by the support and overlapping the swinging member when in closed position, the housing being spaced from the support, the face of the housing opposed to the support being open, a keeper carried by the swinging member and extending between the housing and support when the member is closed, locking means within the housing, and means for projecting the locking means 35 through the open face of the housing to engage the keeper when the swinging member is closed.

3. In combination with a support and a swinging member coacting therewith, a housing carried by the support and overlapping the swinging member when in closed position, the housing being spaced from the support, the face of the housing opposed to the support being open, a keeper carried by the 50 swinging member and extending between the housing and support when the member is closed, locking means within the housing, and means for projecting the locking means through the open face of the housing to engage the keeper when the swinging member is closed, said housing being provided with cleanout openings.

4. In combination with a support and a swinging member coacting therewith, a housing carried by the support and overlapping the swinging member when in closed position, the housing being spaced from the support, the face of the housing opposed to the support being open, a keeper carried by the 60 swinging member and extending between the

housing and support when the member is closed, locking means within the housing, and means for projecting the locking means through the open face of the housing to engage the keeper when the swinging member 70 is closed, the outer corner portions of the housing being cut away to provide cleanout openings.

5. In combination with a support and a swinging member coacting therewith, a housing carried by the support and overlapping the swinging member when in closed position, the housing being spaced from the support, the face of the housing opposed to the support being open, a keeper carried by the 75 swinging member and extending between the housing and support when the member is closed, a rotatable boss extending within the housing through a wall thereof, a shank disposed through the boss, said shank and boss 80 having unitary rotation, a locking plate within the housing and rotating with the shank, rotation of the shank in one direction bringing the plate into locking engagement with the keeper when the swinging member 85 is closed, and means for rotating the shank.

In testimony whereof I hereunto affix my signature.

THEODORE JOHNSON.
